UNITED STATES PATENT OFFICE.

CARL W. DEAN AND RANSOM HUNT, OF NODE, WYOMING; SAID HUNT ASSIGNOR TO
SAID DEAN.

TRACK-LINING JACK.

1,171,931.

Specification of Letters Patent.

Patented Feb. 15, 1916.

Application filed November 16, 1914. Serial No. 872,492.

To all whom it may concern:

Be it known that we, CARL W. DEAN and RANSOM HUNT, citizens of the United States, residing at Node, in the county of 5 Niobrara, State of Wyoming, have invented certain new and useful Improvements in Track-Lining Jacks; and we do hereby declare the following to be a full, clear, and exact description of the invention, such as 10 will enable others skilled in the art to which it appertains to make and use the same.

This invention relates to track lining jacks.

The object of the invention resides in the 15 provision of a jack of this character by means of which track rails may be brought into proper alinement with minimum effort and through the instrumentality of a single workman.

With the above and other objects in view the invention consists in the details of construction and in the arrangement and combination of parts to be hereinafter more 20 fully described and particularly pointed out 25 in the appended claims.

In describing the invention in detail reference will be had to the accompanying drawings wherein like characters of reference denote corresponding parts in the several views, and in which—

Figure 1 is a side elevation of a track lining jack constructed in accordance with the invention, and showing the device in position for alining a section of track; Fig. 35 2, a plan view of what is shown in Fig. 1, and Fig. 3, an end view of same.

Referring to the drawings the improved track lining jack is shown as comprising a base member A formed of spaced angle 40 irons 10 and 11 connected together in any suitable manner. Pivoted between the angle irons 10 and 11 is a rail engaging lever 12 one end of which is forked to form arms 13 and 14. The jack further comprises a 45 toothed arm 15 having one end pivotally mounted between the irons 10 and 11, while the other end thereof extends between the arms 13 and 14. An operating lever 15' is pivoted between the arms 13 and 14, the end 50 thereof adjacent the lever 12 being forked to form arms 16 and 17 between which are pivotally mounted pawls 18 and 19 adapted to coöperate with the teeth of the arm 15. Pivoted between the irons 10 and 11 is an

angle lever 20 one end of which is connected to the lever 12 by link 21. 55

In the use of the device the base A is placed beneath the rail section to be lined and the lever 12 disposed in substantially horizontal position, in which disposition of 60 the lever 12 the pawls 18 and 19 will engage the teeth of the arm 15 adjacent the inner end of said arm. The operating lever 15' is then moved upwardly on the pawl 19 as a pivot. This movement of the operating 65 lever will raise the lever 12 and position the pawl 18 in engagement with another tooth of the arm 15. The lever 15' is then moved downwardly with the pawl 18 as a pivot and the pawl 19 thus engaged with 70 an advance tooth on the arm 15. The lever 15' is then again elevated which will further raise the free end of the lever 12 and force the rail laterally. This operation is repeated until the rail is properly lined. 75 During this operation the angle lever 20 and the inner end of the lever 12 will be forced into the ground and act as a brace to assure efficient operation of the device by positively holding same against slipping. 80

What is claimed is:—

1. A track lining jack comprising a base member, an arm pivoted to said base member, a rail engaging lever pivoted to the base member and slidably engaged at its free end with said arm, and an operating lever pivoted to the rail engaging lever and engageable with said arm when moved in one direction to elevate the free end of the rail engaging lever. 90

2. A track lining jack comprising a base member, a toothed arm pivoted to said base member, a rail engaging lever pivoted to the base member and slidably engaged at its free end with said arm, an operating lever pivoted to the rail engaging lever, a pawl pivoted to the operating lever and engageable with the teeth of the arm when said operating lever is moved in a direction to raise the free end of the rail engaging lever, and a second pawl pivoted to the operating lever and engageable with the teeth of the arm to support the rail engaging lever during opposite movement of the operating lever. 95 100

3. A track lining jack comprising a base member, an arm pivoted to said base member, a rail engaging lever pivoted to the base 105

member and slidably engaged at its free end with said arm, an operating lever pivoted to the rail engaging lever and engageable with said arm when moved in one direction to elevate the free end of the rail engaging lever, a brace lever pivoted to the base member, and a link connecting one end of said lever to said rail engaging means.

In testimony whereof, we affix our signatures, in the presence of two witnesses.

CARL W. DEAN.
RANSOM HUNT.
